(57) **CLAIM**

The ornamental design for wrist supporting device, as shown and described.

DESCRIPTION

FIG. 1 is a view of a wrist supporting device in accordance with the first embodiment of my new design;

FIG. 2 is a front perspective view thereof;

FIG. 3 is a bottom view thereof;

FIG. 4 is a top view thereof;

FIG. 5 is a right side view thereof;

FIG. 6 is a left side view thereof;

FIG. 7 is a front view thereof;

FIG. 8 is a rear view thereof;

FIG. 9 is a front perspective view of a wrist supporting device in accordance with the second embodiment of my new design;

FIG. 10 is a bottom view thereof;

FIG. 11 is a top view thereof;

FIG. 12 is a right side view thereof;

FIG. 13 is a left side view thereof;

FIG. 14 is a front view thereof; and,

FIG. 15 is a rear view thereof.

The dash-dot-dot-type broken lines illustrate unclaimed environment and form no part of the claimed design. The evenly-spaced broken lines on the wrist supporting device illustrate stitching that is included as part of the claimed design.
